UNITED STATES PATENT OFFICE.

OLIVER J. BICKMORE, OF OLDTOWN, MAINE.

SINGLE-USE POWDER-BOX.

1,262,165.

Specification of Letters Patent. Patented Apr. 9, 1918.

Application filed February 14, 1916. Serial No. 78,233.

To all whom it may concern:

Be it known that I, OLIVER J. BICKMORE, citizen of the United States, residing at Oldtown, Maine, have invented certain new and useful Improvements in Single-Use Powder-Boxes, of which the following is a specification.

My invention is designed to provide a single use powder container with means for 10 ejecting the powder by pressure through the use of a bulb.

I propose to make the box in substantially two parts, one to contain the powder and the discharge tube, and the other to contain 15 the bulb or pressure device for ejecting the powder and to secure these two parts together in a single container or package sealed as it is sent out from the factory but capable of ready use by unsealing the exit 20 opening for the powder and removing a section of the wall of the container to expose the bulb to the pressure of the finger.

In the accompanying drawing,

Figure 1 is a section of one form of container, and

Fig. 2 is a view of a modification.

In carrying out my invention I make the powder box or container of suitable material, pasteboard or metal, this being shown 30 at A, having its upper end closed as at a, and provided with a central depending tube b, a cap c covering the top and having a weakened portion d in line with the opening of the tube which can be removed before 35 the device is used, this serving as a seal until it is removed. The lower end of the part A has a brace e, which may be of any suitable construction to prevent collapsing of the container, and it also tends to support 40 the central tube near its lower end. The tube as shown is flared at its extreme lower end as at f, and a space is left between the end of the tube and the bottom of the powder receptacle, the walls of which curve inwardly as at g so as to direct the powder to the space beneath the flaring end of the tube for a purpose hereinafter described.

The powder receptacle has a flanged connection h, and in filling the receptacle the powder is placed within the part A through the open lower mouth formed by the flange h and after it has been suitably filled the part A is fitted through the flange h to the part B and after the parts are in place the two 55 parts are held together and sealed by an outer wrapping C. The part B has a per-

forated bottom section i and a rubber bulb D is held between two disks or partitions k, l, with a nipple m extending through the partition l and into the flaring lower end of the tube b. The rubber bulb D may be of the ordinary atomizer type having an intake valve n and an outlet valve o, so as to prevent the powder from falling through into the bulb. An opening is formed in the 60 wall of the part B to expose a part of the bulb as at p so that this may be pressed by the finger to eject the air out through the nozzle m into the pipe b which will have the effect of entraining the powder falling down 65 the curved walls g into the flaring mouth, and up and out through the opening of the pipe b the pressure of air being sufficient for this purpose. When the package goes out from the factory the opening q in the wall 70 of the part B will be sealed by a part of the outer wrapper as at r, but this will be weakened around the edges of the opening and suitably inscribed so as to indicate that it is to be removed in order to expose a part of 75 the bulb.

As shown in Fig. 2, instead of having the ejecting pipe centrally arranged I may incline it to one side so as to have it discharge the powder at the edge of the box instead 85 of centrally thereof.

It will be seen that by this construction I produce a single use powder box which may be made so cheaply as to warrant its being thrown away after its supply of powder has 90 been used. By reason of the curved walls the powder is fed directly to the flared opening so that every bit of the powder in the box may be used and there will be no waste. By sending the package out perfectly sealed 95 there is no danger of waste in shipment and there can be no deterioration of the powder by exposure to the air.

The cap c may be made capable of turning, or any means may be provided for closing 100 the exit opening temporarily when the device is not being used.

What I claim is:

1. A powder package comprising a container for the powder having a curved bottom, a discharge tube having a flaring intake opening, a bulb having a nozzle extending through the bottom and into the flaring opening of the tube, the bulb having an exposed portion for manipulation, substantially as described. 105

2. A powder package comprising a pow-

der container, an exit tube carried thereby so as to prevent waste, substantially as described. having a depending flaring lower end, a second compartment beneath the powder compartment containing a bulb exposed at one side for manipulation, said bulb having a nozzle projecting into the flaring end of the exit tube, and means for automatically feeding the powder to the center of the container

10

In testimony whereof, I affix my signature in presence of a witness.

OLIVER J. BICKMORE.
